UNITED STATES PATENT OFFICE

2,609,540

BRASSIÈRE WITH ADJUSTABLE BREAST SUPPORTING MEMBERS

Jack J. Lo Cascio, Bayonne, N. J., assignor to Even-Pul Foundations, Inc., New York, N. Y., a corporation of New York

Application January 19, 1951, Serial No. 206,860

2 Claims. (Cl. 2—42)

1

This invention relates to new and useful improvements and structural refinements in brassières, and the principal object of the invention is to facilitate adjustment of the brassière so as to provide a greater or lesser amount of lift to the breasts, whereby the contour of the breast region may be effectively controlled within a relatively wide range of adjustment and whereby the wearer may maintain a desirable bust line regardless of the physical characteristics such as size and shape of her breasts.

In particular, the invention contemplates the provision in a brassière of a pair of pad-shaped breast supporting members which are disposed below the breasts at the outside of the lower portions of the breast cups of the brassière, the pad-shaped members being well adapted to support and impart a lifting effect to the breasts, and adjustable means being provided for increasing or decreasing the amount of support and lift so afforded.

Some of the advantages of the invention reside in its extreme simplicity of construction, in its convenience and expeditious adjustability, in its unique appearance and in its adaptability for embodiment in new brassières as well as for application as an attachment to conventional brassières already in existence.

With the above more important objects and features in view and such other objects and features as may become apparent as this specification proceeds, the invention consists essentially of the arrangement and construction of parts as illustrated in the accompanying drawings, in which:

Figure 1 is a perspective view of a brassière constructed in accordance with the teachings of this invention;

Figure 2 is a vertical sectional view taken substantially in the plane of the line 2—2 in Figure 1; and

Figure 3 is a fragmentary front elevational view showing the attachment of the breast supporting members to the adjustment means, one of the breast supporting members being shown in section.

Like characters of reference are employed to designate like parts in the specification and throughout the several views.

Referring now to the accompanying drawings in detail, the reference character 10 designates a brassière including a front region 12 provided with a pair of breast cups 14, the invention residing in the provision of a pair of pad-shaped elongated breast supporting members 16 which

are disposed at the outside of the lower portions of the respective breast cups 14 so that they are capable of supporting and imparting a lifting effect to the breasts, as will be clearly apparent from Figure 2.

Each of the members 16 is preferably formed from soft, somewhat resilient material, such as molded rubber, plastic, or the like, and is irregular in shape insofar that it is thicker at the center and tapered toward its marginal edges, as well as being substantially wider at the center than at its opposite ends. Generally speaking, the members 16 conform substantially to the size and shape of the lower portions of the respective breast cups 14, although not necessarily so.

In any event, the members 16 are secured at the outer end or side edges thereof as at 18 to the outer side edges of the respective breast cups 14, while the inner end portions of the members 16 have embedded or otherwise attached thereto substantially T-shaped keepers 20 which are disposed in downwardly divergent relation and are formed integrally with the usual slide 22 of an adjustable fastener 24. This adjustable fastener assembly is of a conventional nature, such as for example, that which is illustrated in U. S. Patent No. 2,437,765 granted to N. Statham, on March 16, 1948, the fastener assembly 24 being vertically disposed and secured by stitching 26 to the front portion 12 of the brassière between the breast cups 14, as is best shown in Figure 1.

The slide 22 also includes the usual pull tab 28, and it will be apparent from the foregoing that by simply shifting the slide 22 upwardly or downwardly on the fastener, the inner end portions of the breast supporting members 16 may be raised or lowered, thus correspondingly varying the amount of support and lift which is imparted to the breasts by the members 16. By virtue of their configuration, the members 16 not only lift the breasts but also properly support the same as aforesaid, it being obvious that the adjustment facilitated by the means 22, 24 will permit the breasts, confined within the breast cups, to be lifted as well as projected forwardly to the desired degree.

Needless to say, the invention may be embodied in new garments, or it may be applied in the nature of an attachment to brassières already in existence, in which event it would only be necessary to stitch the outer ends of the members 16 to the brassière, as at 18, and to similarly secure the fastener 24 to the front central portion of the brassière, as at 26.

It is believed that the advantages and use

of the invention will be clearly understood from the foregoing disclosure and accordingly, further description thereof at this point is deemed unnecessary.

While in the foregoing there has been shown and described the preferred embodiment of this invention, it is to be understood that minor changes in the details of construction, combination and arrangement of parts may be resorted to without departing from the spirit and scope of the invention as claimed.

Having described the invention, what is claimed as new is:

1. A brassière having a front region including a pair of breast cups, a pair of elongated pad-shaped breast supporting members disposed at the outside of the lower portions of the respective breast cups, means securing outer ends of said members to the front region of the brassière at the outer side edges of the respective cups, a fastener mounted on said front region between the cups and including a vertically adjustable slide, and a pair of inverted substantially T-shaped keepers depending in downwardly divergent relation from said slide, said keepers being embedded in the inner end portions of the respective breast supporting members, whereby the latter may be raised or lowered relative to the cups.

2. A breast supporting attachment for brassières and similar garments, said attachment comprising a pair of elongated pad-shaped breast supporting members adapted to underlie the breast cups of a brassière and secured to the brassière at their outer ends, a fastener provided between inner ends of said members and adapted for attachment to the stated brassière between the breast cups, said fastener including an upwardly and downwardly adjustable slide, and a pair of inverted substantially T-shaped keepers depending in downwardly divergent relation from said slide, said keepers being embedded in the inner end portions of the respective breast supporting members.

JACK J. LO CASCIO.
